POWER TRAIN FOR SUGAR HARVESTERS

Vernon P. Broussard, P.O. Box 227,
St. Martinville, La. 70582

Continuation-in-part of abandoned design application Ser.
No. 11,429, Apr. 12, 1968. This application Dec. 18,
1969, Ser. No. 20,558

Term of patent 14 years

Int. Cl. D15—03

U.S. Cl. D40—1

FIG. 1.

FIG. 2.

FIG. 1 is a perspective view of the front left side of the power train for sugar harvesters showing my new design, and

FIG. 2 is a perspective view of the rear right side thereof.

The broken lines are for illustrative purposes only.

This application is a continuation-in-part of design patent application, Ser. No. D11429, filed April 12, 1968, and now abandoned.

I claim:

The ornamental design for a power train for sugar harvesters, as shown and described.
